[57] CLAIM

The ornamental design for a crib footboard, as shown and described.

DESCRIPTION

FIG. 1 is a front view of a crib footboard of the present invention;

FIG. 2 is a side view thereof;

FIG. 3 is a top view thereof;

FIG. 4 is a sectional view thereof taken along the plane of line 4—4 of FIG. 1;

FIG. 5 is a sectional view taken along the plane of line 5—5 of FIG. 1; and

FIG. 6 is a sectional view taken along the plane of line 6—6 of FIG. 1.

The rear side is a mirror image of the front side except for a flat bottom panel as shown in FIG. 4.

The tiny feet members shown by means of dotted lines in FIGS. 1, 2 and 3 are for illustrative purposes only.
